UNITED STATES PATENT OFFICE.

FRANK M. WOJCIECHOWSKI, OF NORTH ATTLEBORO, MASSACHUSETTS, ASSIGNOR TO MARATHON COMPANY, OF ATTLEBORO, MASSACHUSETTS, A CORPORATION OF MASSACHUSETTS.

DESIGN FOR A DOCUMENT CASE.

Application filed April 21, 1923. Serial No. 5,892. Term of patent 3½ years.

To all whom it may concern:

Be it known that I, FRANK M. WOJCIECHOWSKI, a citizen of the United States of America, residing at 78 Grant Street, North Attleboro, Massachusetts, have invented a new, original, and ornamental Design for a Document Case, of which the following is a specification, reference being had to the accompanying drawing, forming a part thereof.

In said drawing, the Figure 1 is a front view of a document case showing my new design, and Figure 2 is an edge view thereof.

I claim:

The ornamental design for a document case substantially as shown and described.

Signed by me at Attleboro, in the county of Bristol and Commonwealth of Massachusetts, this eighteenth day of April, 1923.

FRANK M. WOJCIECHOWSKI.
